[57] CLAIM

The ornamental design for a bottle, as shown and described.

DESCRIPTION

FIG. 1 is a perspective view of a bottle showing my new design;

FIG. 2 is a side elevational view thereof;

FIG. 3 is a view taken from the right of FIG. 2;

FIG. 4 is a view taken from the side opposite that shown in FIG. 2;

FIG. 5 is a view taken from the left of FIG. 2;

FIG. 6 is a top plan view thereof;

FIG. 7 is a bottom plan view thereof; and,

FIG. 8 is an exploded perspective view similar to FIG. 1 but with the closure for the bottle removed.
